APPARATUS FOR CONTINUOUSLY ENAMELING THIN SHEET METAL

Robert G. Calton, Nashville, Tenn.

Application January 3, 1951, Serial No. 204,156

2 Claims. (Cl. 118—33)

1

This invention relates to apparatus for porcelain enameling sheet metal and has more particular reference to apparatus for continuously applying porcelain enamel to thin sheet steel or thin sheet iron.

In the firing of porcelain enameled sheet iron of 20 gauge or lighter, it has been the practice to either support the article in a horizontal plane on spaced pins or the like, or to hang the article from hooks on a chain which carries the articles through a firing zone. It has never been possible heretofore to fire large flat pieces thinner than 20 gauge by either of these procedures without warpage. If the workpiece has rested on the conventional firing pins in a horizontal position, the base metal was softened during the firing operation to an extent sufficient to cause sagging in the areas between the pins and noticeable deformation in the supported areas. A sheet thus fired with the base metal deformed will always show the presence of such deformed area because of the reflective nature of the porcelain enamel coating. Furthermore, the cooled sheet was severely warped and did not present an adequate flat surface. When the sheets have been hung from hooks and fired by being carried through a furnace, the sheets usually warped, due, not only to the weight of the sheet itself, but also the inherent stresses which are present in the sheet. Thin sheets, that is, thinner than 20 gauge, when fired in this way, also tend to exhibit an overall "crinkled" effect due to the unequal softening of the sheet in local areas and the internal stresses in the sheet, as aforesaid.

It is, therefore, a principal object of this invention to provide novel and improved apparatus for continuously porcelain enameling sheet metal ranging from 20 to 40 gauge, without the enameled sheet metal showing areas of deformation.

Another object of the invention is to provide apparatus, as above characterized, including means for controlling the tension of the moving sheet as it moves through the firing furnace to prevent buckling and warping thereof, due to the firing temperature.

A further object of the invention is to provide apparatus, as above characterized, including a firing furnace having an arch for supporting and guiding the sheet during its travel therethrough.

Other objects and advantages of the invention will appear in the specification when considered in connection with the accompanying drawings, wherein:

Fig. 1 is a diagrammatic elevational view of the apparatus of the invention, with parts broken

away to show the interior of certain of the elements;

Fig. 2 is a diagrammatic plan view of the apparatus shown in Fig. 1;

Fig. 3 is a detailed perspective view showing the manner in which the rollers are mounted; and

Fig. 4 is a detailed perspective view showing the manner in which the tension control idle rollers are mounted.

10 This invention is related to the subject matter of my co-pending application, Ser. No. 125,087, filed Nov. 2, 1949, and entitled "Methods of and Apparatus for Porcelain Enameling Sheet Metal."

The present invention, insofar as it concerns 15 the application of vitreous enamel or frit paste to a continuously moving thin sheet of metal and the firing of the coated sheet, is similar to the invention disclosed and claimed in my said co-pending application. Here, however, the similarity ceases, 20 and many improvements and advantageous features are incorporated in the invention of the present application.

Referring now to the drawings, and more particularly to Figs. 1 and 2, there is shown a coiled roll 10 of sheet metal 11, ranging from 20 to 40 gauge, mounted on a horizontal spindle 12. The sheet passes through driven rollers 13 and then through a vat 14 filled with a nickel sulfate solution of approximately 12 oz./gallon, the sheet being held below the surface of the solution by means of idle roller 15.

From the nickel sulfate solution, the sheet passes over idle roller 16, then through a drying chamber 17, which may comprise heat lamps 18, or other suitable heating elements, where the sheet is dried. The excess nickel sulfate solution is wiped off both sides of the sheet as it emerges from the vat. From the drying chamber, the sheet passes through driven rollers 19 into and through a vat 20 filled with ground coat 35 enamel slip or frit paste of any suitable composition, where the sheet is coated with a coating of the slip. The sheet is held below the surface of the slip by means of idle roller 21.

40 From the coating vat 20, the sheet passes over a rubber stripper or squeegee 22, which removes the enamel slip from the bottom of the sheet, and then through a firing furnace 23, shown diagrammatically as being heated electrically by resistors 24. It is to be understood that the heat may be applied in any other suitable manner.

45 During its passage through the firing furnace, the sheet is supported by and slides over the upper surface of a metal arch 25. The arch 25 is 50 wider than the sheet and is preferably made in 55

three sections, an intermediate section 26 made of nickel alloy to withstand the firing temperature, and end sections 27 made of any suitable material preferably metal. The upper surface of the arch is flat in transverse cross section.

From the furnace 23 the fired sheet passes under a sag control device 28, through driven rollers 29, into a second coating vat 30 identical to the vat 20. The second coating vat is filled with cover coat enamel slip or frit paste of the desired color and composition. The sheet is held below the surface of the slip by means of idle roller 31.

From the coating vat 30, the sheet passes over a rubber stripper or squeegee 32, which removes the enamel slip from the bottom of the sheet, and then through a second firing furnace 33, which is identical in construction to the first firing furnace 23. During its passage through the second firing furnace 33, the sheet is supported by and slides over the upper surface of a metal arch 34, which is identical in construction to the arch 25 in the first firing furnace.

The sheet emerges from the second firing furnace 33 as the finished product. As the finished product emerges from the second firing furnace 33, it passes under a second sag control device 35 and then through driven rollers 36. The sheet emerging from the driven rollers 36 may be cut to suitable length or rolled into a coil 37.

The driven rollers 13, 19, 29 and 36 are identical in construction and, as shown in Fig. 3, each comprises a lower roller 38 journaled in fixed bearing blocks 39 supported by a suitable frame 40; an adjustable upper roller 41 journaled in bearing blocks 42 vertically slidably mounted in the frame 40 and carrying compression springs 43; vertically adjustable sliding blocks 44 slidably mounted in the frame 40 and engaging the upper ends of the coiled springs; and adjusting screws 45 for vertically adjusting the position of the sliding blocks 44 so that the springs 43 will tightly and resiliently hold the upper roller in engagement with the lower roller. Both the upper and lower rollers are preferably made of resilient composition material and may be covered with asbestos or the like.

The driven rollers 13 and 19 are driven through suitable gearing such as a shaft 46 having gears 47 and 48 fixed thereto and adapted to engage and drive suitable gears 49 and 50 on the roller shafts of the fixed roller of each pair of driven rollers 13 and 19, respectively. The shaft 46 is rotated by a constant speed motor 51 through suitable reduction gearing 52.

The driven rollers 29 and 36 are driven at constant speed by motors 53 and 54 through suitable reduction gearing 55, 56 connected to the lower rollers of the respective pairs of driven rollers.

The sag control devices 28 and 35 are identical in construction and, as shown in Fig. 4, each comprises an idle roller 57 journaled between the outer ends of arms 58, 59 pivotally mounted on suitable frames 60. The rollers 57 ride freely on the upper surface of the moving sheet and are of sufficient weight to hold the sheet taut against the upper surfaces of the arches in the respective furnaces. Added weight may be applied to the roller shafts to provide for the desired tensioning of the sheet.

Positioned above the arm 58 of the roller 57 of the slack control device 28 is a limit switch 61 connected upon being operated to start motor 51 which operates the driven rollers 13 and 19.

Positioned below the arm 58 of the roller 57 of the slack control device 28 is a second limit switch 62, connected upon being operated to stop the motor 51. The construction and arrangement is such that with all motors running and the sheet moving through the apparatus, any slack developed in the sheet, due to its expansion in the first firing furnace, will cause the arm 58 carrying the roller 57 to move downwardly and engage the limit switch 62 to stop the motor 51, thus permitting the driven rollers 29 and 36 to take up the slack. When the arm 58 moves upwardly as the slack is taken up, it will engage the limit switch 61 and start the motor 51 so that the sheet will move through the first furnace along its predetermined line of travel.

The slack control device 35 operates in a similar manner to take up any slack developed due to expansion of the sheet in the second furnace. Positioned above the arm 58 carrying the idle roller 57 of the slack control device 35 is a limit switch 63 connected when operated to start motors 51 and 53, which drive the driven rollers 13, 19 and 29. Positioned below the arm 58 of the slack control device 35 is a second limit switch 64 connected when operated to stop motors 51 and 53.

When the sheet expands, due to the temperature in the second firing furnace, the arm 58 engages the limit switch 64 and stops the motors 51 and 53. The motor 54 continues to run and take up the slack in the sheet. When the arm 58 moves upward into engagement with the limit switch 63, the motors 51 and 53 will be started again and the sheet will move through the second furnace along its predetermined line of travel.

From the foregoing description, it will be readily seen that there has been provided novel and improved apparatus for continuously porcelain enameling thin sheet iron, including means for maintaining the sheet under sufficient tension while being fired to prevent buckling and warping, whereby the finished product will be free of warping or areas of deformation and have a continuous glossy surface free of blemishes.

While the ground coat and cover coat of frit paste or slip has been shown as being applied by dipping, obviously, these coats may be sprayed on just before the moving sheet enters the firing chamber, if desired.

Obviously, the invention is not restricted to the particular embodiment thereof herein shown and described.

What is claimed is:

1. For use in apparatus for continuously porcelain enameling sheet iron of the class wherein a coil of 20-40 gauge sheet iron mounted on a horizontal spindle is fed by means of a plurality of horizontally spaced pairs of gripping and feeding rollers in succession through means for applying frit paste to the upper surface of the moving iron sheet and through a furnace having substantially horizontally aligned inlet and outlet openings therein, in which the frit paste is fused on the moving iron sheet; the combination with said furnace of means for preventing the moving iron sheet from buckling and warping during its passage through the furnace, including an arched support mounted in said furnace and extending between the inlet and outlet openings therein and over which the moving iron sheet is adapted to slide; and a tensioning member engaging the upper surface of said moving iron sheet for holding the sheet taut in sliding engagement with

the upper surface of the arched support as it passes through the furnace, whereby the sheet will be prevented from buckling and warping due to the high heat in the furnace.

2. Apparatus as set forth in claim 1, wherein said tensioning member comprises a pivotally mounted idle tensioning roller.

ROBERT G. CALTON.
